United States Patent Office.

J. C. WANDS, OF NASHVILLE, TENNESSEE.

Letters Patent No. 61,899, dated February 5, 1867.

IMPROVEMENT IN ROOFING.

The Schedule referred to in these Letters Patent and making part of the same.

TO ALL WHOM IT MAY CONCERN:

Be it known that I, J. C. WANDS, of Nashville, in the county of Davidson, and State of Tennessee, have invented a new and improved Mode of Fastening Roofing; and I do hereby declare the following to be a full, clear, and exact description of the same, sufficient to enable one skilled in the art to which the invention appertains, to make use of it, reference being had to the accompanying drawings which form a part of this specification, and in which—

Figure 1 is a perspective view.

Figure 2 is a transverse section.

Figures 3 and 4 are plan and section, respectively, of the roofing material.

The breadths of fabric, felt, or prepared paper, or covered wire cloth, are laid parallel upon the roof from ridge to eaves, their edges lapping each other upon raised strips, which are capped with metallic plates, which fasten the lapped edges on the strips, making a water-tight joint. It is principally designed for car roofs, which are subjected to strain that springs them up and down, cracking the roofing material on the sheathing. In this roof the material is held by its edges forming lapped water-tight joints, while the fabric between the points of support is at liberty to stretch or collapse. In the drawings—

A is the sheathing of the roof, which should be laid close and well. B are angular strips, reaching from the ridge to the eaves, fastened to the sheathing or through it to the rafters. C are breadths of fabric, felt, paper, or other suitable material, prepared as customary. I herein propose to introduce a new material for the purpose, and show a mode of fastening effectually either it or any other material. The fabric or paper H is of such width as to lap its edges over the top of each ridge which bounds the space it occupies, and thus each breadth will lap upon its neighbor on each side, a water-proofing material being laid between the two if desired, and the metallic angular plate D being laid over the lapping edges, fastening them firmly to the strip B by screws or otherwise. This mode of securing the edges of the strips so as to complete the roof may be adopted under all circumstances where the roofing fabric, felt or paper is the material, but it is especially intended for car roofs, which in the swaying of the cars and the motions of their contents become wound and twisted to some extent, which cracks the material if it be fastened on the sheathing. By my plan it is firmly held by the edge, and has the opportunity, in the intervals between the strips B, of expanding and collapsing to the extent required without cracking. The ends of the material being lapped over the eaves may be secured by metal plate G. The material shown in figs. 3 and 4 consists of a layer of wire cloth, covered with any pitchy substance on the outside, and with a coat on the inside to prevent its adherence to the sheathing of the roof. a represents the wire cloth, b the tarry or other water-proof covering, and c is a thickness of paper.

Having described my invention, what I claim therein as new, and desire to secure by Letters Patent, is—

The mode of fastening the edges of the fabric by lapping between the angular strips B and the bent metallic plate D, substantially as described and represented.

To the above specification of my improved mode of fastening roofing, I have signed my hand this fourth day of December, 1866.

J. C. WANDS.
